UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

1,387,117.

Specification of Letters Patent.

Patented Aug. 9, 1921.

Application filed January 16, 1920. Serial No. 351,788.

To all whom it may concern:

Be it known that I, FRED S. CARR, a citizen of the United States, and a resident of Newton, in the county of Middlesex, Commonwealth of Massachusetts, have invented an Improvement in Separable Fasteners, of which the following description, in connection with the accompanying drawings, is a specification, like characters on the drawings 10 representing like parts.

This invention pertains to improvements in separable fasteners, and more particularly, though not exclusively, to separable fasteners in which one or both parts are adapted to be metallically secured to their carrying fabrics.

It is among the objects of the invention to provide a separable fastener in which the fabric carrying the stud and socket shall be brought into adjacency, thereby avoiding that separation which normally amounts to substantially the thickness of the stud and socket when engaged one with the other.

Referring to the drawings, in which I have shown an illustrative embodiment of 20 one form of my invention:

Figure 1 is an elevation of two pieces of fabric held together by a preferred form of fastener;

Fig. 2 is a section on the line 2—2 of Fig. 1;

Fig. 3 shows two pieces of fabric held together by a plurality of such fasteners;

Fig. 4 is a plan view of the preferred form 30 of socket prior to attachment thereof to the fabric; and

Fig. 5 is a section on the line 5—5 of Fig. 4, being partly in elevation.

Referring to the drawings and to the preferred form of my invention selected for 40 illustrative purposes, I have shown a stud 6 secured to fabric 7, preferably expanding the base 8 into a stud-securing element, herein shown as a flanged disk 9, thereby to 45 secure the stud to the fabric, preferably without perforation of the fabric, and with the neck of the stud closely adjacent the general plane of the fabric 7. The preferred form of securing the stud herein 50 illustrated and described is claimed in my copending application filed herewith, Serial No. 351,780.

The preferred form of socket illustrated 55 herein includes a casing 10 containing a spring 11, the casing 10 preferably having a

stud-receiving aperture 12 which is notched to provide a lateral lock and is described in my copending application, Serial No. 307,111, filed June 27, 1919. This socket is preferably applied to the socket-carrying fabric 13 in such a way as to bring the face of the fabric 13 approximately in line with that face of the socket from which the stud is intended to enter. I preferably perform this attachment by providing a socket-at- 60 taching element 14 having a flanged-over rim 15 into which may expand a part carried by or forming a part of the socket, herein shown as an expansible disk 16 divided into six parts, of which three are preferably as 65 shown thrown downward to engage beneath the flange 17 of the socket and of which three are thrown upward so that when the casing 70 10 is pressed against the socket-engaging part 14, with the fabric 13 interposed there- 75 between, the projecting portions of the part 16 will expand and press the fabric beneath the flange 15, thus securing the socket to the fabric while the fabric is thrown forward into a position approximating the plane of 80 the face of the socket.

Where the two pieces of fabric to which the stud and socket are secured are thus thrown into adjacency, a lateral strain on the two pieces of fabric will produce sub- 85 stantially no tipping movement between the stud and socket and therefore the stud and socket will not tend to become accidentally unfastened under lateral strain.

It will be understood that I use the word 90 "fabric" in its broader sense to include not only woven materials, but any flexible carrying medium.

While I have shown and described a preferred form of one embodiment of my invention, it will be understood that changes involving omission, substitution, alteration and reversal of parts, and even changes in the mode of operation, may be made without departing from the scope of my invention, 95 100 which is best defined in the following claims.

Claims:

1. A socket for separable fasteners having a casing for location on one side of the fabric to which the socket is to be attached, a 105 socket-securing element having a flanged-over rim for location on the opposite side of the fabric to which the socket is to be attached, said casing providing expansible means adapted to be pressed into said socket- 110

securing element, with the fabric between said expandable means and the socket-securing element, thereby to press the fabric beneath the flange of the socket-securing element while said expandable means is expanded by pressure exerted through the fabric against the socket-securing element.

2. A socket for separable fasteners having a dished casing providing a flange, and an

expandable part secured to said casing by 10 said flange; and socket-securing means including a flanged-over rim beneath which said expandable part may press the fabric to secure the socket to the fabric and hold said parts in assembled relationship.

In testimony whereof, I have signed my name to this specification.

FRED S. CARR.
